UNITED STATES PATENT OFFICE

134,635

DESIGN FOR A REMOVABLE TIRE TREAD PROTECTOR

George Lee Snyder, Whistler, Ala., assignor of
one-half to James Franklin Farrar, Mobile,
Ala.

Application February 10, 1942, Serial No. 105,745

Term of patent 3½ years

To all whom it may concern:

Be it known that I, George Lee Snyder, a citizen of the United States, residing at Whistler, in the county of Mobile and State of Alabama, have invented a new, original, and ornamental Design for a Removable Tire Tread Protector, of which the following is a specification, reference being had to the accompanying drawing, forming part thereof.

Figure 1 is a side elevational view of a re-

movable tire tread protector showing my new design.

Figure 2 is a top plan view, and

Figure 3 is a sectional view taken on the line 3—3 of Figure 1.

I claim:

The ornamental design for a removable tire tread protector, as shown.

GEORGE LEE SNYDER.
